UNITED STATES PATENT OFFICE.

ROBERT BENSON CRAIG, OF CALGARY, AND ALLEN EUGENE COX, OF OKOTOKS,
ALBERTA, CANADA.

AUTOMATIC TIME-SWITCH.

1,245,572.

Specification of Letters Patent. Patented Nov. 6, 1917.

Application filed July 24, 1916. Serial No. 110,999.

To all whom it may concern:

Be it known that we, ROBERT BENSON CRAIG, a citizen of Canada, and ALLEN EUGENE COX, a citizen of the United States, and 5 residing, respectively, at Calgary and Okotoks, both in the Province of Alberta, in the Dominion of Canada, have jointly invented new and useful Improvements in Automatic Time-Switches, of which the following is a 10 specification.

Our invention relates to improvements in an automatic time switch and the object of our invention is to enable the illumination of display or advertising matter for a pre- 15 arranged period of time without supervision.

We attain this by the mechanism illustrated in the accompanying drawings, in which—

20 Figure 1. is a plan of the device with the ordinary dial and hands removed for the sake of clearness.

Fig. 2. a section showing the trip lever resting on the dial having returned to the 25 normal position after the passing of the trip pin U.

Fig. 3. a section through the gear wheel which carries the hour hand.

Fig. 4. a part plan of the gear wheel showing the ratchet wheel.

Fig. 5. a section through the large dial.

Fig. 6. a plan of the large dial and ratchet underneath.

Fig. 7. a section of the ratchet for the 35 upper dial.

Fig. 8. a plan of the upper dial ratchet.

Fig. 9. a section of the upper dial.

Fig. 10. a plan of the upper dial.

40 Figs. 11, 12. are section and plan respectively of the friction collar.

Fig. 13. an elevation of the trip lever rest.

Fig. 14. the elevation of the trip lever.

Similar letters refer to similar parts throughout the several views.

45 A; is an ordinary clock movement with a 24 hour dial having a gear wheel with a long cannon pin, to which said gear wheel is fastened a ratchet wheel G. H; the lower dial which carries the fixed trip pin U, is 50 divided into 24 parts which may be numbered, has a ratchet and spring underneath which engages on the ratchet wheel G, in such a manner as to allow only a forward movement of the dial for setting purposes.

K; is the ratchet wheel for the upper dial I, 55 which said ratchet wheel is sweated on to the cannon pin and acts as a friction collar for the dial H; I; is the upper dial provided with a ratchet and spring and having slots T, in which slots are movable trip pins M. 60 The friction collar L, holds the dials in position on the cannon pin, and as the dials revolve the trip pins U, and M, raise the trip lever D, release the sprocket wheel C, allowing a quarter turn of the switch which is 65 driven by the spring P, F; is a wire spring which brings the trip lever to the dial after the passing of the trip pin. E; is the bracket which supports the trip lever and the spring F. N; is a small piece of insulation directly 70 under the switch. O; is the main insulation directly under the switch. B; is the switch which may be of any rotary type. Q; is an insulation ring between the contact breaker and the vertical spindle of the switch. U; 75 is the fixed trip pin on the dial H. M; is the movable trip pin, in the dial I, which can be put out of action by pushing to the center of the dial. The number of these trip pins may be varied as required. 80

The dials "h" and "i" having a rotary motion on the cannon pin "g" and not being attached thereto but merely held in position by friction collars in the shape of ratchet wheels, adjustments may be made to each 85 dial independently thereby giving any desired period of time between the operation of any two cams.

Further than this—the dials making one complete revolution every twenty-four hours 90 each cam will operate the trip lever only once in that period and by setting the cams in position display or other matter may be illuminated for any desired period without the necessity of personal attention, an advantage to store keepers who do not reside in close proximity to their store.

We are aware that prior to our invention automatic time switches have been made using dials operating on a cannon pin. We 100 do not therefore claim such a combination broadly but—

What we do claim as our invention, and desire to secure by Letters Patent is:—

1. The combination in an automatic time 105 switch of a series of dials mounted on a cannon pin the dials placed one above the other, the upper dial being diametrically smaller

than the dial below, the said dials having slots cut radially from a point near the center to a point near the circumference in which slots are trip pins the upper edges of which coact on a trip lever and operate an electric switch all substantially as set forth.

2. The combination in an automatic time switch of a series of dials mounted on a cannon pin, the dials placed one above the other, the upper dial being diametrically smaller than the dial below, the said dials

having radial slots in which are movable trip pins which said trip pins may be rendered inoperative by moving toward the center of the dial all substantially as set forth.

Calgary, Canada, 17th July 1916.

ROBERT BENSON CRAIG.

ALLEN EUGENE COX.

Signed in the presence of—

WILFRID J. GRAY,

J. S. CRAIG.
